UNITED STATES PATENT OFFICE.

GEORGE P. TAYLOR, OF CLINTON, MASSACHUSETTS.

DESIGN FOR SHEETING.

SPECIFICATION forming part of Design No. 33,937, dated January 22, 1901.

Application filed December 5, 1900. Serial No. 38,846. Term of patent 14 years.

To all whom it may concern:

Be it known that I, GEORGE P. TAYLOR, a citizen of the United States, residing at Clinton, in the county of Worcester and State of Massachusetts, have invented and produced 5 a new and original Design for Sheeting, of which the following is a specification, reference being had to the accompanying drawing, forming a part thereof.

10 My invention relates to woven textile fabrics, and more particularly to what is termed "sheeting;" and it consists in a new and original design for sheeting, as will be herein-after fully described.

15 The drawing is a plan view of a detached section of sheeting, showing my design.

In the accompanying drawing the section of sheeting is represented by a series of straight lines, the transverse lines *a* of which extend in 20 the direction of the width of the sheeting and represent the filling-threads and are arranged at an equal distance apart, while the lines *b*, which extend in the direction of the length of the sheeting and represent the warp-threads, 25 are arranged at an unequal distance apart. The lines *b* at the central portion of the sheeting are arranged near together for some distance on either side of the central line of the sheeting and at an equal distance apart, while 30 the lines *b* on either side of the central uni-

formly distant lines gradually vary in their distance apart toward the edges of the sheeting, being at the greatest distance apart near the selvage edges. Along the edges of the sheeting are arranged the longitudinal lines 35 *b*, close together and at a uniform distance apart. The appearance of the sheeting is that it has a central striped effect of closely-arranged longitudinal lines *b* and a stripe on either side of said central stripe formed by 40 the threads *b* at a varying distance apart and a stripe on either edge of the sheeting formed by lines *b* at an equal distance apart and close together.

The essential feature of my design consists 45 of a greater number of longitudinal lines *b* at the central portion of the sheeting and a less number of lines *b* on either side of the central lines and arranged at varying distances apart and a series of lines *b* at the outer edges 50 arranged close together at an equal distance apart.

What I claim is—

The design for sheeting, substantially as shown and described.

GEO. P. TAYLOR.
